WILLIAM F. JAMES, OF HONOLULU, TERRITORY OF HAWAII.

OIL-TANK VALVE.

1,398,025.

Specification of Letters Patent. Patented Nov. 22, 1921.

Application filed May 20, 1920. Serial No. 383,005.

To all whom it may concern:

Be it known that I, WILLIAM F. JAMES, a citizen of the United States, and a resident of Honolulu, in the Territory of Hawaii, have invented a new and Improved Oil-Tank Valve, of which the following is a full, clear, and exact description.

This invention relates to improvements in oil tank valves, an object of the invention being to provide an improved construction of double acting valve for use in tanks or reservoirs from which the fluid is required to be fed intermittently into a chamber or receptacle below in which the level is maintained constant by liquid seal action.

A further object is to provide an improved construction of parts in which a removable cap for the tank operates the valve which controls the outlet from the tank and so construct the parts as to prevent the simultaneous removal of the cap and the valve, but permit the independent opening of either so that the tank can be refilled from time to time without danger, and the liquid can be discharged from the tank as occasion may require.

Heretofore, with tanks or reservoirs supplying oil to stoves and the like, it has been necessary to remove the tanks from the stoves and turn them up-side-down in order to refill said tanks. With my improved construction, the tank can be refilled without removal and while in normal operative position.

A further object is to provide an improved construction of tank and valve control therefor, which may be adapted for use in connection with water coolers or for any other analogous purpose.

With these and other objects in view the invention consists in certain novel features of construction, and combinations and arrangements of parts, as will be more fully hereinafter described and pointed out in the claims.

In the accompanying drawings—

Figure 1 is a view in longitudinal section illustrating my invention.

Fig. 2 is a view in section through the tank at right angles to Fig. 1, but showing the valve control in elevation.

Fig. 3 is an end view of the cup 4.

Fig. 4 is an inverted plan view of the cap 18.

1 represents a supply tank which, we will assume for purposes of description, is to be

employed as an oil supply tank for oil stoves. This tank 1 has secured therein a tubular valve casing 2. The lower end of this valve casing 2 is projected through the bottom of the tank 1 and is secured therein by means of solder 3 or other securing means. A cup 4, which constitutes a ring, is secured to the upper end of the tubular casing 2 and projects through the top of tank 1 and is secured in place by means of solder 3 or other securing means.

5 represents a tubular outlet spout which has an enlarged upper end 6 screwed into the threaded lower end of the tubular casing 2, as shown at 7, and forming at its upper end a seat for a valve 8. The lower end of this tube or spout 5 is adapted to be projected into a compartment and maintain a level of liquid therein by being submerged, or partially submerged, in the liquid, as indicated at 9 in Fig. 1.

The valve 8, above referred to, is secured to the lower end of a stem 10 which projects upwardly in the casing 2 and is provided with flattened sides 11 which are engaged by parallel pins 12, said pins projecting through the casing 2 and operating to hold the stem 10 against rotary movement, but permit longitudinal movement of the stem 85 to open and close the valve. A collar 13 is located around the stem 10 against the pins 12 and a coiled spring 14 is positioned around the stem and located between the collar 13 and the valve 8, said spring tending to hold the valve normally on its seat.

The extreme upper end of the stem 10 is screw threaded, as shown at 15, and these threads are engaged by internal screw threads 16 in a tubular shank 17 on a rotary cap 18. The cap 18 fits in the cup 4 and is provided with a gasket 19 secured to its lower face by means of a nut 20 screwed onto the shank 17 so that said cap 18 with its gasket 19 constitutes a valve seating 100 against the upper end of the casing 2 and the bottom of cup 4 to form an airtight closure for the tank 1.

To prevent possibility of the cap 18 and the valve 8 from being simultaneously removed from the casing 2, I provide the upper end of the cup 4 with an annular flange 21 and provide inwardly projecting lugs 22 on the cap 18 which project under the flange 21. Recesses 23 are provided in the flange 21 to permit the removal of the cap after the latter has been turned slightly

to free the shank 17 from engagement with the threads 15, but ordinarily the lugs 22 are under the flange 21 and while they permit a free rotary turning of the cap, will 5 prevent a longitudinal movement of the cap while it is in threaded engagement with the stem 10.

The tubular casing 2 adjacent its lower 10 end is provided with an annular series of openings 24 and at its upper end with an annular series of openings 25 for the passage of liquid therethrough.

The operation is as follows: When it is 15 desired to fill the tank 1, the cap 18 is removed leaving the valve 8 held in a closed position by the action of the spring 14. Liquid can now be poured through the open upper end of the tubular casing 2, and will flow through the openings 25 into the tank 20 1 but cannot flow out.

When it is desired to discharge liquid 25 from tank 1 through the outlet tube 5, the cap 18 on being replaced is turned to the right, so that the internally screw threaded shank 17 by reason of its engagement with the threads 15 will cause the stem 10 to move upwardly, thus lifting the valve 8 from its seat and allowing the liquid in tank 1 to flow through the openings 24 and outlet tube 30 5, air entering the tank by the same passages to take its place. This flow will be maintained until the level of the liquid in a lower reservoir, as indicated at 9, rises high enough to seal the end of the outlet tube 5. 35 It will be noticed that the gasket 19 in the cap 18 hermetically seals the upper opening in the tubular valve casing 2 before the lower valve 8 can open. The valve 8 is closed by the spring 14 when the cap 18 is 40 turned to the left in the direction opposite to that just described.

It will also be noticed that it is impossible 45 to lift the lower valve 8, and the upper cap valve 18 simultaneously, because when the cap valve 18 is turned to the left to a position for removal, its threads will be disconnected from the threads of the stem, and hence the device is practically fool-proof, it being impossible for the fluid in tank 1 50 to pour directly through the openings 24 and tube 5 into the lower reservoir or font unless the cap 18 has been properly screwed into place, thus closing tightly the upper valve gasket 19 on its seat, otherwise disastrous results might ensue as is well known in the art.

While I have described my invention as applied to fuel tanks for oil stoves, I would have it understood that I desire to cover the 60 device broadly for other fluids, and for any other use to which it can be put; such for instance, as in water coolers of the type so common, wherein the large bottle or water container has to be inverted over the cooler 65 after having been removed for filling.

Various slight changes might be made in the general form and arrangement of parts described without departing from the invention, and hence, I do not limit myself to the precise details set forth, but consider myself 70 at liberty to make such changes and alterations as fairly fall within the spirit and scope of the appended claims.

I claim:

1. The combination with a tank, of a tubular valve casing secured in the tank, an outlet valve at the lower portion of the tubular casing, a removable cap constituting a valve on the upper portion of the tubular casing, a stem on said first-mentioned valve 80 having a screw threaded end, means holding the stem against rotary movement, and an internally screw threaded shank on the cap engaging the threads of the stem.

2. The combination with a tank, of a tubular valve casing secured in the tank, an outlet valve at the lower portion of the tubular casing, a removable cap constituting a valve on the upper portion of the tubular casing, a stem on said first-mentioned valve having 90 a screw threaded end, means holding the stem against rotary movement, an internally screw threaded shank on the cap engaging the threads of the stem, and a spring around the stem normally holding the first-mentioned valve in closed position.

3. The combination with a tank, of a tubular valve casing secured in the tank and having openings adjacent its respective ends, an outlet tube secured in the lower end of the casing and forming a valve seat, a valve at the lower end of the casing normally engaging said seat, a stem on said valve having flattened sides, a pair of pins projected through the casing and engaging the flat 105 sides of the stem holding the latter against rotary movement, a collar around the stem engaging the pins, a coiled spring around the stem between the collar and the valve holding the latter normally in closed position, and a removable cap operatively engaging the stem and adapted to raise and lower the valve when said cap is turned.

4. The combination with a tank, of a tubular valve casing secured in the tank and having openings adjacent its respective ends, an outlet tube secured in the lower end of the casing and forming a valve seat, a valve at the lower end of the casing normally engaging said seat, a stem on said valve having flattened sides, a pair of pins projected through the casing and engaging the flat sides of the stem holding the latter against rotary movement, a collar around the stem engaging the pins, a coiled spring around the stem between the collar and the valve holding the latter normally in closed position, said stem having a screw threaded upper end, a rotary cap located at the upper 120 end of the casing, and an internally screw 130

threaded shank on the cap engaging the threads of the stem.

5. The combination with a tank, of a tubular valve casing secured in the tank and having openings adjacent its respective ends, an outlet tube secured in the lower end of the casing and forming a valve seat, a valve at the lower end of the casing normally engaging said seat, a stem on said valve having flattened sides, a pair of pins projected through the casing and engaging the flat sides of the stem holding the latter against rotary movement, a collar around the stem engaging the pins, a coiled spring around 30 the stem between the collar and the valve holding the latter normally in closed position, a cup secured around the upper end of the casing and projecting above the tank, a cap fitting said cup and constituting a valve 35 40 therein, an internally screw threaded tubular shank on the cap, said stem having a screw threaded upper end engaging the threads of the shank, an outwardly projecting flange on the cup at its upper edge, inwardly projecting lugs on the cap normally located under the flange, and said flange having recesses therein for the passage of the lugs to permit removal of the cap.

6. The combination with a tank, of a tubular valve casing secured in the tank and hav-

ing openings adjacent its respective ends, an outlet tube secured in the lower end of the casing and forming a valve seat, a valve at the lower end of the casing normally engaging said seat, a stem on said valve having flattened sides, a pair of pins projected through the casing and engaging the flat sides of the stem holding the latter against rotary movement, a collar around the stem engaging the pins, a coiled spring around 35 the stem between the collar and the valve holding the latter normally in closed position, a cup secured around the upper end of the casing and projecting above the tank, a cap fitting said cup and constituting a valve 40 45 therein, an internally screw threaded tubular shank on the cap, said stem having a screw threaded upper end engaging the threads of the shank, an outwardly projecting flange on the cup at its upper edge, inwardly projecting lugs on the cap normally located under the flange, and said flange having recesses therein for the passage of the lugs to permit removal of the cap.

WILLIAM F. JAMES.
